TENTERING MACHINE

John Kreeft, Haledon, N. J., assignor to Morrison Machine Co., Paterson, N. J., a corporation of New Jersey

Application October 21, 1943, Serial No. 507,077

3 Claims. (Cl. 26—62)

This invention relates to cloth tentering machines of the class characterized by a pair of endless chains each of which is extended around wheels and which chains are arranged side by side but spaced apart and include as links thereof tentering clips which, when the chains are advancing with their inner stretches travelling in the same direction, grip the cloth, the opposed thus-active clips of the two chains being caused to stretch the cloth by being made somewhat to diverge from each other while they are undergoing transit as parts of such chain stretches. Each clip has a lower jaw as a part of its body structure and an upper jaw pivoted to said structure and normally urged into position to coact therewith so as to grip the cloth but which, when the clip in its circuitous travel as a part of the chain approaches or is about to depart from the cloth at the beginning and end of said stretch of the chain, is moved from the lower jaw by suitable means respectively to permit the cloth to enter the clip and the clip to depart from the cloth.

During travel of the clips in the mentioned stretch of either chain they have heretofore been supported against the resistance of the cloth to stretching primarily by a guideway facing outward or away from the opposite chain and at one side of, as below, the plane of the cloth, and by a secondary guideway, as one overhanging a part of each clip remote from its jaws, which merely prevents the clips from tilting around the primary guideway as, in effect, a fulcrum, this being an incident, partly of course of unbalanced weight of the clips, but mainly due to resistance of the cloth to stretching imposed above, that is, at one side of, such fulcrum. In time, wear of the guideways, as of course also the clips, occurs so that the clips sag—that is to say, in such manner that their gripping means press the gripped portion of the cloth downwardly or out of the plane in which the cloth is intended to be stretched, or the plane in which such stretching occurred in the initial or unworn state of the parts; in other words, the clips cease to act only as intended, or only to stretch, but also act to press the cloth, which has the effect of misshaping it, leaving it not flat as it entered the machine but more or less bulged as an incident of the pressure. This condition eventually becomes so serious that the guideways and, in fact also, the clips have to be replaced with new ones or in some way reconditioned, in any event a quite expensive procedure.

According to this invention I have overcome this fault primarily by so constructing the machine that each clip, while travelling as a part of the mentioned inner stretch of the chain of which it forms a part, obtains bearings on guideways disposed both sides of the plane of stretching the cloth, or what I term the gripping plane of the machine, being that plane which is coincident with the two lines in which the two chains are intended to act, in stretching the cloth, to grip the latter.

In the drawings, Fig. 1 is a cross-sectional view of so much of a tentering machine constructed in accordance with my invention as is here material;

Fig. 2 shows a clip contributing to my invention, as seen from its inner side;

Fig. 3 is a fragmentary plan of the part of the fixed structure which provides the upper guideway, the clamping devices being removed; and

Fig. 4 is a longitudinal vertical section of what appears in Fig. 3.

Fixed structure is shown at 1, including a bed 2 which may be of any length toward and from the observer in Fig. 1 and has depressed lateral ledges 3, such bed being of course duplicated, or one for each chain. Each such bed provides bearings for the mentioned two wheels (not shown, but one at each end thereof) around which the corresponding chain extends and one of which is a suitably driven sprocket-wheel. At 4 is shown one of the two usual circular openers, which as usual are also positioned at the ends of the bed and serve to engage the movable jaw of each clip to shift it to the open position (or out of gripping relation to the fixed jaw) during movement of the clips around the corresponding wheel. The left side of the bed in Fig. 1 is what I term its inner side, being the side adjacent the other bed and hence the cloth. A rail or flange upstands at the free margin of each ledge, comprising a metal strip 5 and a phenolite strip 6 between strip 5 and the bed, which rail affords a guideway for the chain clips, the right-hand or relatively outer rail being sufficient in itself as a guideway since the corresponding stretch of the chain is subject only to the weight of each clip to tilt it. But with the relatively inner or left-hand rail another guideway is to cooperate, thus:

On and extending lengthwise of the bed is a guiding structure formed as follows: A series of bosses 7, seated on the bed, have projecting upwardly and inwardly therefrom arms or stand-

ards 8 which are connected with a rail parallel with the bed; this rail comprises a cross-sectionally L-shaped body portion 9, formed with one flange thereof projecting horizontally outward, or to the right in Fig. 1, and the other downward, and a phenolite strip 9a secured to the outer face of the latter flange by screws 10, the outer face of the strip being in a plane coincident with the outer face of the rail 5—6 at the left side of the bed. The guiding structure is clamped to the bed so as to be adjustable thereon inwardly and outwardly as follows: At suitable intervals the bosses are clamped by screws 11 penetrating transverse slots 12 in them and tapped into the bed. The remaining bosses are formed with longitudinal slots 13 penetrated by screws 14, also tapped into the bed, and eccentrics 15, occupying such slots, are penetrated by the screws 14. By releasing all the screws the guiding structure may be adjusted inward or outward, to wit, by rotating the eccentrics, whose heads 15a, which are made by the screws to exert direct clamping pressure on the bosses, are here formed with radial holes 15b to receive a spanner or equivalent wrench. The fixed structure thus includes guideways at 9—9a and 5—6 which face outwardly and are arranged at opposite sides of, or here one below and the other above, the mentioned gripping plane.

Each clip comprises a body providing, as usual, the fixed jaw and, pivoted therein, the movable jaw. The base 16 of the body is formed with a depending link portion 16a by which it is pivoted, as at 17, to the next adjoining links (one such link being shown in part at 18 in Fig. 2) and which has a vertical plane face 16b to wipe the outer face of rail 5—6, and at 16c is the usual inwardly extending horizontal plate forming the fixed jaw of the clip. Upstanding from the base and overhanging the fixed jaw is an arm 19 in which is pivoted at 20 the usual lever 21 providing the movable jaw of the clip, coacting with the fixed jaw to grip the cloth. This arm has an upward projection 22 provided at 22a with a plane vertical face to wipe the outer face of rail 9—9a.

Thus, according to my invention, guideways are provided for each clip at both sides of the gripping plane x of the clip, each active in a direction directly opposite to that in which the cloth, in resisting stretch, tends to move the clip. Thus such wear as occurs may be equally distributed at both sides of the gripping plane and it tends to proceed at the same rate and so as always to preserve the surfaces as they become worn parallel with their original state, or not skewed therefrom as in the case of the conventional machine where each clip functions as a lever in acting to stretch. If one of the strips 6 and 9a should wear

at a faster rate than the other the guiding structure including strip 9a may be adjusted in the way explained.

To support the clips they may obtain contact 5 with the ledge 3 and the upper surface of rail 5—6.

In the appended claims I term the clip-link 16a and the portion of its projection 22 which contacts the rail 9—9a abutments.

10 In the conventional machine the cloth being tentered of course lies in a substantially horizontal plane and in such case I not only provide that the construction shall be as hereinbefore set forth but I place the center of gravity of the clip outward of the plane of contact of the outer face of rail 5—6, in this example by properly weighing for this purpose the projection 22. Thereby whatever tilting the clip tends to undergo is in the direction outward or from the cloth, so that 15 20 the clip itself is not a factor in causing the mentioned bulging of the cloth.

Having thus fully described my invention what I claim is:

1. In a tentering machine, the combination, 25 with fixed structure for guiding the tentering clips of such machine interlinked as components of an endless chain, said structure having, above and below and parallel with and spaced from the plane of the cloth to be tentered, flanges having surfaces facing away from the cloth, of one such clip comprising, with a base in contact with said surface of the lower flange and having an upwardly facing cloth-supporting jaw and an arm overhanging the jaw, a movable jaw pivoted in said arm and normally urged into cloth-gripping relation to the first-named jaw, said arm itself having an upward projection in contact with said surface of the upper flange.

2. The combination set forth in claim 1 characterized by the center of gravity of the clip being outward of the vertical plane in which the base contacts said surface of the lower flange.

3. In a tentering machine, the combination, 45 with an elongated substantially horizontal bed having a substantially horizontal flange presenting a surface facing away from the cloth to be tentered, of an elongated structure carried by the bed and including, above and substantially parallel with and spaced from said flange, 50 a rail also presenting a surface facing away from the cloth to be tentered, and independent means, supported by the bed and engaged with said structure at spaced points lengthwise thereof, for adjusting the latter crosswise of itself toward or from the cloth, said surfaces of said flange and rail affording guiding means for an endless chain of cloth-engaging tentering devices.

JOHN KREEFT.
